UNITED STATES PATENT OFFICE.

WILLIAM SMITH, HORRY, OF NIAGARA FALLS, NEW YORK, ASSIGNOR, BY MESNE ASSIGNMENTS, TO BURROUGHS ADDING MACHINE COMPANY, OF DETROIT, MICHIGAN, A CORPORATION OF MICHIGAN.

ADDING-MACHINE.

No. 899,983.

Specification of Letters Patent. Patented Sept. 29, 1908.

Application filed September 26, 1903. Serial No. 174,779.

To all whom it may concern:

Be it known that I, WILLIAM SMITH HORRY, a subject of King Edward of Great Britain, residing at Niagara Falls, in the county of Niagara and State of New York, have invented certain new and useful Improvements in Adding-Machines, of which the following is a specification.

My invention relates to electric operating devices for adding machines and the like, and has for its object the production of novel and more efficient means for this purpose than have been heretofore devised, all as herein-after more fully explained and particularly 15 pointed out in my claims.

In the accompanying drawings—Figure 1 is a perspective view of one form of my attachment applied to an adding machine; Fig. 1^a is a view of the mechanism for returning the actuating shaft of the machine to its normal position after it has been operated by the motor. Fig. 2 is an enlarged detail view of a form of contact device which may be employed with the device illustrated 25 in Fig. 1; Fig. 3 is a diagrammatic representation of a modified form of circuit; Fig. 4 shows a modified construction of circuit breaker; and Fig. 5 shows a twisting magnet which may be substituted for the motor as a 30 means for actuating the shaft of the adding machine.

The same reference numerals are employed to indicate corresponding parts in the several views.

In Fig. 1 of the accompanying drawing I have illustrated my invention as applied to a familiar type of adding machine known as the Burroughs machine, such machine comprising an adding mechanism and a printing mechanism controlled and operated by a plurality of numbered keys 1, and a handle or operating lever 2, the ordinary operation of the machine consisting in depressing or setting the proper keys to represent the 45 amount of the item to be added and printed and then pulling forward the operating lever to its limit of movement and releasing it, suitable resetting springs within the machine, as illustrated in Fig. 1^a serving to restore it 50 and the parts moved by it to normal position.

The main operating shaft of the machine, through which power is transmitted to the adding and printing mechanisms, is a rock shaft 2^a, and where the machine is to be

manually operated by means of the hand- 55 lever 2 such lever is secured to this shaft. Where the machine is to be operated by my novel electric operating devices, however, the hand lever will preferably be omitted, although I have shown it present in Fig. 1 60 for the purposes of the foregoing explanation.

Under my invention the power for operating the machine is supplied by an electric motor 4 suitably geared or otherwise connected with the operating shaft 2^a of the machine, in the present instance by means of a gear 5 fast upon said shaft and meshing with a pinion 6 fast upon the end of the motor shaft. The motor 4 (of rotary or constant torque type), is located in an electric circuit 70 A' B' adapted to be supplied with current from any suitable source. This motor circuit is provided with two breaks or points of opening, one controlled by a manually operated circuit closer or switch at 3, and the 75 other controlled by a circuit-breaker or switch 8 arranged to be automatically operated by the motor. In the present instance the switch 8 is normally closed and the switch 3 normally open. Upon closing the switch 3 80 by hand current will flow through the motor circuit and actuate the motor, and when the motor shaft has made approximately one revolution in the direction of the arrow in Fig. 1 an arm 7 fast upon and insulated from it, adjacent the switch 8, will contact with the latter and swing it forward, and thereby open the circuit and stop the flow of current. 85

The relative sizes of the gear 5 and pinion 6 are such that the revolution of the motor 90 shaft just described will serve to turn the operating shaft 2^a of the machine forward to its limit of movement, and when the circuit is automatically opened at the switch 8, at the 95 end of such revolution of the motor shaft, the resetting springs 14 within the machine, as illustrated in Fig. 1^a which have been put under tension by the forward movement given the operating shaft, will return all the 100 parts, including the motor shaft, to normal position. As the motor shaft approaches such position (moving in a direction opposite that indicated by the arrow in Fig. 1), its arm 7 will contact with the forward side of the switch 8 and swing the latter backward to normal position, thereby again closing the 105 motor circuit at this point. If the circuit has been held closed at the switch 3, and con-

tinues to be after the motor shaft has returned to normal position and again closed the circuit at the switch 8, the motor will be instantly reenergized and the operation repeated; while if the circuit has been opened at the switch 3 during the return movement of the parts the closing of the switch 8 will have no effect upon the motor and it will remain at rest until the switch 3 is again closed.

10 The manual circuit-closer or switch at 3 may be of any suitable construction, but in the present instance I have provided a novel self-locking magnetic switch, of such construction that when the switch is closed and the current thereby permitted to flow through the circuit, the switch will be magnetically held in closed position until the circuit is opened at the switch 8, whereupon the cessation of flow of current will release the

15 magnetic switch and permit it to open. The details of the particular form of magnetic switch which I have provided in the present instance are illustrated in Fig. 2, where the contact terminals of the circuit, indicated at

20 12 and 13, are adapted to be closed together by depression of the movable member or spring arm 9 of the switch, which is provided with a push-button 9^a for the purpose. Located beneath the movable member 9 of the

25 switch is an electro-magnet 10, whose coils are included in the motor circuit. When the spring arm 9 is depressed to close said circuit at the contacts 12, 13, and the current thereby permitted to flow through the circuit and

30 35 coils of the magnet 10, the pole-piece 11 of the core of the magnet will attract the spring arm 9 and hold it in depressed position, with the circuit closed at the contacts 12, 13, so long as current continues to flow. When the

35 40 circuit is opened at the switch 8, in the manner heretofore described, the cessation of flow of current will deenergize the magnet 10 and release the arm 9, which will then spring upward to normal position and open

45 the circuit at the contacts 12, 13.

As will be understood from the foregoing, with the provision of my self-locking magnetic switch 3, it is simply necessary to touch the push-button 9^a and close the switch, 50 whereupon the motor will be set in operation and the switch be held closed until the motor shaft has completed its positive movement and opened the switch at the other break in the circuit, thereby rendering it unnecessary 55 to either manually hold the switch 3 closed during the operation of the machine, or to provide mechanical means, in the form of latches and the like, for so doing.

In adding machines of the character described, it is frequently desirable to add and list or print the same amount several times in succession, to which end machines of this character are provided with what is termed a "repeating key," indicated at C in Fig. 1. 65 When the numbered keys representing any

given amount are depressed and this repeating key then depressed, and held or latched in its lower position, the numbered keys will not be released and restored to normal position at the end of each operation of the machine, so that by pulling the operating handle forward and releasing it a number of times in succession the amount represented by the depressed keys may be added and printed a corresponding number of times. 70 My novel electric operating device lends itself to this "repeating" operation to great advantage, since after setting the proper numbered keys and the repeating key it is simply necessary to depress the push-button 75 of the switch 3 and hold it depressed until the machine has been given the desired number of operations by the motor, it being understood that under such circumstances the motor shaft will make one revolution and its arm 7 open the switch 8, whereupon it will be returned to normal position by the resetting springs within the machine, and upon reaching such position its arm 7 will automatically close the switch 8 again, whereupon, the circuit being maintained closed at the manually-operated switch 3, the motor will be immediately reenergized and the operation repeated so long as the switch 3 is held closed. 90

It is not essential that the self-locking magnetic switch shall form part of or be immediately associated with the manual circuit-closer, as in the construction illustrated in Figs. 1 and 2. On the contrary, it may be located at any point in the circuit and the push-button be employed simply as a circuit-closer to initially close the circuit, whereupon the magnetic switch will be energized to close the circuit at another point and maintain it closed until the circuit is automatically opened by the motor at the switch 8 or such other switch as may be substituted for the latter. Thus in Fig. 3 I have illustrated a modified form of the device in which a button 9^a is mounted upon the adding machine in convenient proximity to its keys, all other portions of the mechanism being placed at any convenient distance therefrom. In this case the movable core 11' of the solenoid 10' acts upon the momentary closing of the circuit through the button or key 9^a to move the lever 9 into position to close the circuit between the mercury cup contacts 12, 13, and through the field 4' of the motor 4 and the circuit breaker 8. The operation then takes place as above described with reference to Figs. 1 and 2. 110

As will be understood from the foregoing description of Fig. 3, the solenoid 10' and its core 11', together with the lever 9 operated by said core and coöperating with the contacts 12, 13, constitute a magnetic switch which operates to close a branch line across the motor circuit A' B' in shunt of or multi- 115 120 125 130

ple with the push button 9^a so that when the circuit is closed through such branch the position of the switch 9^a becomes immaterial, and it may instantly open, after being depressed, without opening the circuit through which the current for operating the motor is flowing. When the motor circuit is opened at the switch 8, however, the solenoid magnet is deenergized and the weight of its core swings the opposite end of the lever 9 upward and opens the motor circuit at the contacts 12, 13.

The circuit breaker 8 as above illustrated may comprise merely a double pole switch or various other forms of construction may be used, as will be obvious to those skilled in the art. For instance, I have shown in Fig. 4 a form of circuit breaker in which contact is made between an insulated arm 7' secured to the armature shaft and a conductive strip 8' while the former is moving through an arc corresponding to the required twist of the shaft of the adding machine, say 63°. The initial position of the arm 7' is indicated in full lines at P' and its final position in dotted lines at P². It will be noticed that the armature has broken its own circuit at the breaker in moving from P' to P², so that it moves no more. Also, the circuit being broken, the core 11' is released and the circuit is thus broken at the contacts 12, 13 as well,—a double break. In returning, which it instantly does on the breaking of the circuit, impelled by the springs of the adding machine acting through the shaft, the contact is again made at the circuit breaker 8', but remains broken at the button contacts 12, 13. If then the button is pressed for an instant one reciprocatory motion of the shaft is made. It will be obvious that in this case the armature shaft may be directly connected to the printing and spacing shaft of the adding machine.

A suitable motor powerful enough to operate the machine can be procured for any kind of current used for electric lighting, so that the precise motor to do the work is immaterial to the practice of my invention. It is not even necessary to employ a motor but I may use instead a twisting magnet as indicated in Fig. 5. This twisting magnet comprises a field F and an armature A and is preferable in some respects to the motor, being adapted for use with either direct or alternating currents. Upon establishing the current through the field of the magnet the armature A, which may be attached or geared to the shaft of the adding machine, is turned through an angle of about 90°, thereby operating said shaft. The circuit being broken at the proper point through a circuit breaker operated or controlled by the magnet, the several parts return instantly to their original positions.

Inasmuch as the motor or magnet ac-

quires considerable momentum in its travel, and as this momentum increases with the speed of the operation, it is desirable that some means be provided for preventing the motor from inflicting a blow upon the adding machine at the end of its forward stroke. This may be accomplished in many ways, as, for instance, by such construction that the circuit is broken earlier than would otherwise be necessary, so that the momentum is absorbed by the time the travel is completed. One such construction is illustrated in Fig. 1, in which the circuit breaker 8 is adapted to be opened slightly in advance of the completion of one revolution of the armature shaft. A somewhat earlier opening of the circuit may be provided for by a suitable lug upon the arm 7, or by a proper extension of the contacting portion of the circuit breaker, as indicated in dotted lines on Fig. 1. Similarly in the modification shown in Fig. 4 it is sometimes desirable to make the conductive strip 8' of such length that the arm 7' is in contact therewith during somewhat less than its total travel, as will be readily understood. I may provide a spring connection between the shaft of the adding machine and the motor or magnet so that the jolting effect may be completely obviated. With these precautions there is no noticeable jolting of the machine, and the operation is quiet and satisfactory. While the details of the construction of the adding machine illustrated in the drawings form no part of my invention, reference may be had for an understanding of them to Letters Patent of the United States No. 504,963 and No. 505,078, to William S. Burroughs, and No. 595,864, to William H. Pike, Jr.

I claim:

1. In electric operating means for adding machines and the like, a motor circuit, a motor in said circuit for operating the machine, manually operated means for closing the circuit to energize the motor, and means for automatically opening the circuit at the end of the operating movement of the machine, and closing it to render it responsive to said manually operated means at the end of the return movement of the machine; substantially as described.
2. In electric operating means for adding machines and the like, a motor circuit, a motor in said circuit for operating the machine, manually operated means for closing the circuit to energize the motor, means operated by the motor for opening the circuit at another point at the end of the operating movement of the machine, and means for automatically closing the circuit at the end of the return movement; substantially as described.
3. In electric operating means for adding machines and the like, a motor circuit, a motor in said circuit for operating the ma-

105

125

130

1. *Electric operating means for adding machines and the like, manually operated means for closing the circuit to energize the motor, means operated by the motor for opening the circuit at the end of the operating movement of the machine, and spring operated means for automatically rendering said circuit responsive to said manually operated means at the end of the return movement of the machine; substantially as described.*
2. *4. In electric operating means for adding machines and the like, a motor circuit, a motor in said circuit for operating the machine, manually operated means for closing the circuit to energize the motor, and means operated by the armature of the motor for automatically opening the circuit at the end of the operating movement of the machine, and closing it to render it responsive to said manually operated means at the end of the return movement of the machine; substantially as described.*
3. *5. In electric operating means for adding machines and the like, a motor circuit, a motor in said circuit for operating the machine, manually operated means for closing the circuit at one point, and means for automatically opening and closing the circuit at another point, said opening and closing means operating to open the circuit at the end of the operating movement of the machine, and to close the circuit, to render it responsive to said manually operated means, at the end of the return movement of the machine; substantially as described.*
4. *6. In electric operating means for adding machines and the like, a motor circuit, a motor in said circuit for operating the machine, manually operated means for closing the circuit at one point, means operated by the motor for opening the circuit at another point, and means independent of said motor for automatically closing the circuit again at the latter point; substantially as described.*
5. *7. In electric operating means for adding machines and the like, a motor circuit, a motor in said circuit for operating the machine, manually operated means for closing the circuit at one point, means operated by the motor for opening the circuit at another point, and spring-operated means for automatically closing the circuit again at the latter point; substantially as described.*
6. *8. In electric operating means for adding machines and the like, a motor circuit, a motor in said circuit for operating the machine, manually operated means for closing the circuit at one point, and means operated by the armature of the motor for automatically opening and closing the circuit at another point at intervals determined by the operation of said machine; substantially as described.*
7. *9. In electric operating means for adding machines and the like, a motor circuit, a motor in said circuit for operating the machine, a magnetic switch having its magnet in said circuit for closing the circuit at one point, and means for automatically opening and closing the circuit at another point; substantially as described.*
8. *10. In electric operating means for adding machines and the like, a motor circuit, a motor in said circuit for operating the machine, a magnetic switch having its magnet in said circuit for closing the circuit at one point, and means operated by the motor for opening the circuit at another point; substantially as described.*
9. *11. In electric operating means for adding machines and the like, a motor circuit, a motor in said circuit for operating the machine, a magnetic switch having its magnet in said circuit for closing the circuit at one point, means operated by the motor for opening the circuit at another point, and means for automatically closing the circuit again at the latter point; substantially as described.*
10. *12. In electric operating means for adding machines and the like, a motor circuit, a motor in said circuit for operating the machine, a magnetic switch having its magnet in said circuit for closing the circuit at one point, means operated by the motor for opening the circuit at another point, and spring-operated means for automatically closing the circuit again at the latter point; substantially as described.*
11. *13. In electric operating means for adding machines and the like, a motor circuit, a motor in said circuit for operating the machine, a magnetic switch having its magnet in said circuit for closing the circuit at one point, and means operated by the armature of the motor for automatically opening and closing the circuit at another point; substantially as described.*
12. *14. In electric operating means for adding machines and the like, a motor circuit, a motor having a constant torque located in said circuit and connected to the operating shaft of the machine, manually operated means for closing the circuit at one point, and means for automatically opening the circuit at another point before the machine has completed a cycle of operation, leaving the circuit open at such point during the completion of such cycle of operation and closing the circuit at the same point upon completion of the cycle of operation; substantially as described.*
13. *15. In electric operating means for adding machines and the like, a motor circuit, a motor having a constant torque located in said circuit and connected to the operating shaft of the machine, manually operated means for closing the circuit at one point, and means operated by the motor for opening the circuit at another point before the machine has completed a cycle of operation and leaving the circuit open at such point during the*

completion of such cycle of operation; substantially as described.

16. In electric operating means for adding machines and the like, a motor circuit, a motor having a constant torque located in said circuit and connected to the operating shaft of the machine, manually operated means for closing the circuit at one point, means operated by the motor for opening the circuit 10 at another point before the machine has completed a cycle of operation and leaving the circuit open at such point during the completion of such cycle of operation, and means for automatically closing the circuit 15 again at the latter point upon completion of the cycle of operation; substantially as described.

17. In electric operating means for adding machines and the like, a motor circuit, a motor having a constant torque located in said circuit and connected to the operating shaft of the machine, manually operated means for closing the circuit at one point, means operated by the motor for opening the circuit at 20 another point, and spring-operated means for automatically closing the circuit at the latter point; substantially as described.

18. In electric operating means for adding machines and the like, a motor circuit, a motor having a constant torque located in said circuit and connected to the operating shaft of the machine, manually operated means for closing the circuit at one point, and means operated by the motor shaft for both opening 35 the circuit at another point before the machine has completed a cycle of operation, leaving the circuit open at such point during the completion of such cycle of operation and closing the circuit at the same point upon 40 completion of the cycle of operation; substantially as described.

19. In electric operating means for adding machines and the like, a motor circuit, a motor having a constant torque located in said 45 circuit and connected to the operating shaft of the machine, a magnetic switch having its magnet in said circuit for closing the circuit and maintaining it closed so long as current flows through the coils of the magnet, and 50 means for automatically opening the circuit and closing it again; substantially as described.

20. In electric operating means for adding machines and the like, a motor circuit, a motor having a constant torque located in said 55 circuit and connected to the operating shaft of the machine, a magnetic switch having its magnet in said circuit for closing the circuit and maintaining it closed so long as current 60 flows through the coils of the magnet, and means operated by the motor for opening the circuit; substantially as described.

21. In electric operating means for adding machines and the like, a motor circuit, a motor 65 having a constant torque located in said

circuit and connected to the operating shaft of the machine, a magnetic switch having its magnet in said circuit for closing the circuit and maintaining it closed so long as current flows through the coils of the magnet, means 70 operated by the motor for opening the circuit, and means for automatically closing the circuit again; substantially as described.

22. In electric operating means for adding machines and the like, a motor circuit, a motor having a constant torque located in said circuit and connected to the operating shaft of the machine, a magnetic switch, having its magnet in said circuit for closing the circuit and maintaining it closed so long as current 75 flows through the coils of the magnet, means operated by the motor for opening the circuit, and spring-operated means for automatically closing the circuit; substantially as described.

23. In electric operating means for adding machines and the like, a motor circuit, a motor having a constant torque located in said circuit and connected to the operating shaft of the machine, a magnetic switch having its 80 magnet in said circuit for closing the circuit and maintaining it closed so long as current flows through the coils of the magnet, and means operated by the motor shaft for automatically opening and closing the circuit; 85 substantially as described.

24. In electric operating means for adding machines and the like, a motor circuit, a motor having a constant torque located in said circuit and connected to the operating shaft 100 of the machine, manually operated means for closing the circuit and a magnetic switch for maintaining it closed at a given point, and means for automatically opening and closing it at another point; substantially as 105 described.

25. In electric operating means for adding machines and the like, a motor circuit, a motor having a constant torque located in said circuit and connected to the operating shaft 110 of the machine, manually operated means for closing the circuit and a magnetic switch for maintaining it closed at a given point, and means operated by the motor for automatically opening it at another point; substantially as 115 described.

26. In electric operating means for adding machines and the like, a motor circuit, a motor having a constant torque located in said circuit and connected to the operating shaft 120 of the machine, manually operated means for closing the circuit and a magnetic switch for maintaining it closed at a given point, means operated by the motor for opening it at another point, and means for automatically closing it at the latter point; substantially as described.

27. In electric operating means for adding machines and the like, a motor circuit, a motor 125 having a constant torque located in said

circuit and connected to the operating shaft of the machine, manually operated means for closing the circuit and a magnetic switch for maintaining it closed at a given point, 5 means operated by the motor for opening it at another point, and spring-operated means for automatically closing it at the latter point; substantially as described.

28. In electric operating means for adding 10 machines and the like, a motor circuit, a motor having a constant torque located in said circuit and connected to the operating shaft of the machine, manually operated means for closing the circuit and a magnetic switch 15 for maintaining it closed at a given point, and means operated by the motor shaft for both opening and closing the circuit at another point; substantially as described.

29. In electric operating means for adding 20 machines and the like, a motor circuit, a motor in said circuit for operating the machine, manually operated means for closing the circuit at one point, a magnetic switch having its magnet in said circuit for closing the circuit and maintaining it closed independently 25 of said manually operated means, and means for automatically opening the circuit and closing it again; substantially as described.

30. In electric operating means for adding 30 machines and the like, a motor circuit, a motor in said circuit for operating the machine, manually operated means for closing the circuit at one point, a magnetic switch having its magnet in said circuit for closing the circuit and maintaining it closed independently 35 of said manually operated means, and means operated by the motor for automatically opening the circuit; substantially as described.

40 31. In electric operating means for adding machines and the like, a motor circuit, a motor in said circuit for operating the machine, manually operated means for closing the circuit at one point, a magnetic switch having 45 its magnet in said circuit, for closing the circuit and maintaining it closed independently of said manually operated means, means operated by the motor for automatically opening the circuit, and means for automatically closing it again; substantially as described.

32. In electric operating means for adding 55 machines and the like, a motor circuit, a motor in said circuit for operating the machine, manually operated means for closing the circuit at one point, a magnetic switch having its magnet in said circuit, for closing the circuit and maintaining it closed independently 60 of said manually operated means, means operated by the motor for automatically opening the circuit, and spring-operated means for closing the circuit; substantially as described.

33. In electric operating means for adding 65 machines and the like, a motor circuit, a mo-

tor in said circuit for operating the machine, manually operated means for closing the circuit at one point, a magnetic switch having its magnet in said circuit for closing the circuit and maintaining it closed independently 70 of said manually operated means, and means operated by the motor shaft for automatically opening the circuit and closing it again; substantially as described.

34. In electric operating means for adding 75 machines and the like, a motor circuit, a motor in said circuit for operating the machine, manually operated means for closing the circuit at one point, a magnetic switch having its magnet in said circuit for closing a branch 80 of the motor circuit in shunt of the manually operated means, and means for automatically opening the circuit and closing it again; substantially as described.

35. In electric operating means for adding 85 machines and the like, a motor circuit, a motor in said circuit for operating the machine, manually operated means for closing the circuit at one point, a magnetic switch having its magnet in said circuit for closing a branch 90 of the motor circuit in shunt of the manually operated means, and means operated by the motor for automatically opening the circuit; substantially as described.

36. In electric operating means for adding 95 machines and the like, a motor circuit, a motor in said circuit for operating the machine, manually operated means for closing the circuit at one point, a magnetic switch having its magnet in said circuit, for closing a branch 100 of the motor circuit in shunt of the manually operated means, means operated by the motor for automatically opening the circuit, and spring-operated means for closing it again; substantially as described.

37. In electric operating means for adding 105 machines and the like, a motor circuit, a motor in said circuit for operating the machine, manually operated means for closing the circuit at one point, a magnetic switch 110 having its magnet in said circuit, for closing a branch of the motor circuit in shunt of the manually operated means, means operated by the motor for automatically opening the circuit, and spring-operated means for closing it again; substantially as described.

38. In electric operating means for adding 115 machines and the like, a motor circuit, a motor in said circuit for operating the machine, manually operated means for closing 120 the circuit at one point, a magnetic switch having its magnet in said circuit, for closing a branch of the motor circuit in shunt of the manually operated means, and means operated by the motor shaft for automatically 125 opening and closing the circuit; substantially as described.

39. In electric operating means for adding 130 machines and the like, a motor circuit, a motor in said circuit for operating the ma-

chine, a pair of contacts in said circuit adapted to be closed by a push-button or the like, a magnetic switch for closing the circuit in shunt of the push button and its contacts, 5 the magnet of said magnetic switch being included in said circuit, a switch for opening and closing said circuit at another point, and means for automatically opening and closing said last mentioned switch; substantially as 10 described.

40. In electric operating means for adding machines and the like, a motor circuit, a motor in said circuit for operating the machine, a pair of contacts in said circuit adapted to be closed by a push-button or the like, a magnetic switch for closing the circuit in shunt of the push-button and its contacts, the magnet of said magnetic switch being included in said circuit, a switch for opening 15 and closing said circuit at another point, and means operated by the motor for automatically opening said last mentioned switch; substantially as described.

41. In electric operating means for adding machines and the like, a motor circuit, a motor in said circuit for operating the machine, a pair of contacts in said circuit adapted to be closed by a push-button or the like, a magnetic switch for closing the circuit in shunt of the push button and its contacts, the magnet of said magnetic switch being included in said circuit a switch for opening and closing said circuit, at another point, means operated by the motor for automatically 20 opening said last mentioned switch, and means for automatically closing it; substantially as described.

42. In electric operating means for adding machines and the like, a motor circuit, a motor in said circuit for operating the machine, a pair of contacts in said circuit, adapted to be closed by a push-button or the like, a magnetic switch for closing the circuit in shunt of the push-button and its contacts, the magnet of said magnetic switch being included in said circuit, a switch for opening and closing said circuit at another point, means operated by the motor for automatically 25 opening said last-mentioned switch, and spring-operated means for closing it; substantially as described.

43. In electric operating means for adding machines and the like, a motor circuit, a motor in said circuit for operating the machine, a pair of contacts in said circuit adapted to be closed by a push-button or the like, a magnetic switch for closing the circuit in shunt of the push-button and its contacts, the magnet of said magnetic switch being included in said circuit, a switch for opening and closing said circuit at another point, and means operated by the motor shaft for automatically opening and closing said last-mentioned switch; substantially as described.

44. In electric operating means for adding

machines and the like, a motor circuit, a motor having a constant torque located in said circuit and connected to the operating shaft of the machine, manually operated means for closing the circuit at one point, a magnetic switch having its magnet in said circuit, for closing the circuit and maintaining it closed at another point, and means for automatically opening and closing the circuit at a third point; substantially as described. 70

45. In electric operating means for adding machines and the like, a motor circuit, a motor having a constant torque located in said circuit and connected to the operating shaft of the machine, manually operated means 80 for closing the circuit at one point, a magnetic switch having its magnet in said circuit, for closing the circuit and maintaining it closed at another point, and means operated by the motor for automatically opening the 85 circuit at a third point; substantially as described.

46. In electric operating means for adding machines and the like, a motor circuit, a motor having a constant torque located in said 90 circuit and connected to the operating shaft of the machine, manually operated means for closing the circuit at one point, a magnetic switch having its magnet in said circuit, for closing the circuit and maintaining it closed 95 at another point, means operated by the motor for automatically opening the circuit at a third point, and means for automatically closing the circuit at the latter point; substantially as described. 100

47. In electric operating means for adding machines and the like, a motor circuit, a motor having a constant torque located in said circuit and connected to the operating shaft of the machine, manually operated means 105 for closing the circuit at one point, a magnetic switch having its magnet in said circuit, for closing the circuit and maintaining it closed at another point, means operated by the motor for automatically opening the circuit at a 110 third point, and spring-operated means for automatically closing the circuit at the latter point; substantially as described.

48. In electric operating means for adding machines and the like, a motor circuit, a motor having a constant torque located in said circuit and connected to the operating shaft of the machine, manually operated means for closing the circuit at one point, a magnetic switch having its magnet in said circuit, 120 for closing the circuit and maintaining it closed at another point, and means operated by the motor shaft for automatically opening and closing the circuit at a third point; substantially as described. 125

49. In electric operating means for adding machines and the like, a motor circuit, a motor having a constant torque located in said circuit and connected to the operating shaft of the machine, retracting springs opposing 130

the movement of the motor shaft, manually operated means for closing the circuit to cause the motor to turn its shaft in one direction, and means independent of said manually operated means for automatically opening the circuit and closing it again; substantially as described.

50. In electric operating means for adding machines and the like, a motor circuit, a motor having a constant torque located in said circuit and connected to the operating shaft of the machine, retracting springs opposing the movement of the motor shaft, manually operated means for closing the circuit to cause the motor to turn its shaft in one direction, means operated by the motor, and independent of said manually operated means, for opening the circuit to permit the springs to turn the motor shaft in the opposite direction, and means for automatically closing the circuit again; substantially as described.

51. In electric operating means for adding machines and the like, a motor circuit, a motor having a constant torque located in said circuit and connected to the operating shaft of the machine, retracting springs opposing the movement of the motor shaft, manually operated means for closing the circuit to cause the motor to turn its shaft in one direction, means operated independently of said manually operated means by the motor for opening the circuit to permit the springs to turn the motor shaft in the opposite direction, and means operated by the motor shaft for automatically closing the circuit again; substantially as described.

52. In electric operating means for adding machines and the like, a motor circuit, a motor having a constant torque located in said circuit and connected to the operating shaft of the machine, retracting springs opposing the movement of the motor shaft, manually operated means for closing the circuit at one point to cause the motor to turn its shaft in one direction, and means for automatically opening and closing the circuit at another point; substantially as described.

53. In electric operating means for adding machines and the like, a motor circuit, a motor having a constant torque located in said circuit and connected to the operating shaft of the machine, retracting springs opposing the movement of the motor shaft, manually operated means for closing the circuit at one point to cause the motor to turn its shaft in one direction, and means operated by the motor for opening the circuit at another point to permit the springs to turn the motor shaft in the opposite direction; substantially as described.

54. In electric operating means for adding machines and the like, a motor circuit, a motor having a constant torque located in said circuit and connected to the operating

shaft of the machine, retracting springs opposing the movement of the motor shaft, manually operated means for closing the circuit at one point to cause the motor to turn its shaft in one direction, means operated by the motor for opening the circuit at another point to permit the springs to turn the motor shaft in the opposite direction, and means for automatically closing the circuit again at the latter point; substantially as described.

55. In electric operating means for adding machines and the like, a motor circuit, a motor having a constant torque located in said circuit and connected to the operating shaft of the machine, retracting springs opposing the movement of the motor shaft, manually operated means for closing the circuit at one point to cause the motor to turn its shaft in one direction, means operated by the motor for opening the circuit at another point to permit the springs to turn the motor shaft in the opposite direction, and spring operated means for automatically closing the circuit again at the latter point; substantially as described.

56. In electric operating means for adding machines and the like, a motor circuit, a motor having a constant torque located in said circuit and connected to the operating shaft of the machine, retracting springs opposing the movement of the motor shaft, manually operated means for closing the circuit at one point to cause the motor to turn its shaft in one direction, means operated by the motor for opening the circuit at another point to permit the springs to turn the motor shaft in the opposite direction, and means operated by the motor shaft for automatically closing the circuit at the latter point; substantially as described.

57. In electric operating means for adding machines and the like, a motor circuit, a motor having a constant torque located in said circuit and connected to the operating shaft of the machine, retracting springs opposing the movement of the motor shaft, manually operated means for closing the circuit, and a magnetic switch for maintaining it closed at a given point, to cause the motor to turn its shaft in one direction, and means for automatically opening and closing the circuit at another point; substantially as described.

58. In electric operating means for adding machines and the like, a motor circuit, a motor having a constant torque located in said circuit and connected to the operating shaft of the machine, retracting springs opposing the movement of the motor shaft, manually operated means for closing the circuit and a magnetic switch for maintaining it closed at a given point, to cause the motor to turn its shaft in one direction, and means operated by the motor shaft for

opening the circuit at another point to permit the springs to turn the motor shaft in the opposite direction; substantially as described.

5. 59. In electric operating means for adding machines and the like, a motor circuit, a motor having a constant torque located in said circuit and connected to the operating shaft of the machine, retracting springs opposing the movement of the motor shaft, manually operated means for closing the circuit and a magnetic switch for maintaining it closed at a given point, to cause the motor to turn its shaft in one direction, means operated by the 10 motor shaft for opening the circuit at another point to permit the springs to turn the motor shaft in the opposite direction, and means operated by the motor shaft for automatically closing the circuit again at the latter 15 point; substantially as described.

60. In electric operating means for adding machines and the like, a motor circuit, a motor having a constant torque located in said circuit and connected to the operating shaft 25 of the machine, retracting springs opposing the movement of the motor shaft, manually operated means for closing the circuit at one point, a magnetic switch having its magnet in said circuit for closing the circuit and 30 maintaining it closed at another point, to cause the motor to turn its shaft in one direction, and means for automatically opening and closing the circuit at a third point; substantially as described.

35. 61. In electric operating means for adding machines and the like, a motor circuit, a motor having a constant torque located in said circuit and connected to the operating shaft of the machine, retracting springs opposing 40 the movement of the motor shaft, manually operated means for closing the circuit at one point, a magnetic switch having its magnet in said circuit, for closing the circuit and maintaining it closed at another point, to 45 cause the motor to turn its shaft in one direction, and means operated by the motor for automatically opening the circuit at a third point; substantially as described.

62. In electric operating means for adding 50 machines and the like, a motor circuit, a motor having a constant torque located in said circuit and connected to the operating shaft of the machine, retracting springs opposing the movement of the motor shaft, manually 55 operated means for closing the circuit at one point, a magnetic switch having its magnet in said circuit, for closing the circuit and maintaining it closed at another point, to

cause the motor to turn its shaft in one direction, and means operated by the motor for 60 automatically opening and closing the circuit at a third point; substantially as described.

63. An electrical attachment to an adding machine to twist its shaft against a spring resistance by pressing a button, which embodies a means for completing the circuit by hand, thereby causing a magnet or motor to twist the shaft sufficiently to operate the adding machine, a spring for returning the shaft to its normal position means for keeping the 70 circuit closed while the motor is operating, and means for breaking and making the circuit by the motion, so that the break permits the spring to return the whole apparatus to the starting position for the purpose described.

64. An electrical attachment to an adding machine to twist its shaft against a spring resistance by pressing a button, which embodies a means for completing the circuit by 80 hand, thereby causing a motor or magnet to twist the shaft sufficiently to operate the forward stroke of the adding machine, a spring for returning the shaft to its normal position means for keeping the circuit closed while the 85 motor is operating, and means for breaking and making the circuit by the motion so that the break permits the spring to return the whole apparatus to the starting position and so that the reciprocating motion shall continue until the hand is released.

65. In combination, an adding machine having a shaft adapted to be turned, means for returning the shaft to its original position, an electrical device for turning the shaft, 95 means operated by hand for closing the circuit through said device at one point, and means operated by said electrical device for breaking the circuit at another point, substantially as described.

66. In combination, an adding machine having a shaft adapted to be turned against a spring resistance and to be returned to its original position by said spring, an electrical device for turning the shaft, means operated 105 by hand for closing the circuit through said device at one point, and means operated by said electrical device for breaking the circuit at another point, substantially as described.

In testimony whereof I affix my signature 110 in presence of two witnesses.

WILLIAM SMITH HORRY.
